United States Patent

Des. 236,634
Patented Sept. 2, 1975

236,634

AQUARIUM

Samuel Shalom, 577 Grand St., New York, N.Y. 10013

Filed May 25, 1973, Ser. No. 363,951

Term of patent 14 years

Int. Cl. D30—01

U.S. Cl. D30—6

F I G . 1 .

FIG. 2.

FIG. 3.

FIG. 4.

FIG. 5.

FIG. 6.

FIG. 7.

FIG. 1 is a perspective view of an aquarium showing my new design, illustrating the front and one side thereof;

FIG. 2 is a front elevational view thereof;

FIG. 3 is a right side elevational view;

FIG. 4 is a left side elevational view;

FIG. 5 is a rear elevational view thereof;

FIG. 6 is a cross-sectional view taken along line 6—6 of FIG. 1; and

FIG. 7 is a top plan view thereof.

I claim:

The ornamental design for an aquarium, substantially as shown and described.
